INVENTOR

Charles A. Bailey,
BY
Arthur J. Jenkins,
ATTORNEY.

UNITED STATES PATENT OFFICE.

CHARLES A. BAILEY, OF CROMWELL, CONNECTICUT.

AUTOMATIC LIGHTING AND SOUND-PRODUCING DEVICE.

Application filed October 25, 1920. Serial No. 419,304.

To all whom it may concern:

Be it known that I, CHARLES A. BAILEY, a citizen of the United States, and a resident of Cromwell, in the county of Middlesex and State of Connecticut, have invented new and Improved Automatic Lighting and Sound-Producing Devices, of which the following is a specification.

My invention relates to the class of devices in which a noise and a light may be simultaneously produced, as for alarm purposes, and an object of my invention, among others, is to produce a particularly efficient device of the character described that shall be of simple construction.

One form of device embodying my invention and in the construction and use of which the objects herein set out, as well as others, may be attained, is illustrated in the accompanying drawings, in which—

Figure 1 is a side view of a hand flashlight showing my attachment in face view secured thereto.

Figure 2 is a similar view with the controlling lever removed to display parts underneath, a portion only of the flashlight being shown.

Figure 3 is a side view of the flashlight and attachment illustrating its manner of use.

Figure 4 is a detail view illustrating the parts of the device set ready for operation.

Figure 5 is a view in side elevation of a torch embodying a little different form of operating mechanism.

In the accompanying drawings the numeral 5 indicates the case of a hand flashlight of ordinary construction having a lens 6 for displaying the light, it being understood that the case contains a battery operated in the usual manner, the operating means comprising a switch member 7 adapted to make contact with another switch member to complete the circuit for the electricity and thereby display the light in a manner that will be readily understood by those skilled in the art, all of the parts thus far described being of ordinary and well known construction.

My improved light and sounding device

is shown in the drawings herein as attached to a hand flashlight of ordinary construction, as hereinabove briefly set out, and for this reason further and detailed illustration of this ordinary flashlight is omitted herein. 55 In adapting my invention I provide a base plate 8 that is attached to the case, which case has the switch member or terminal 7 suitably connected with one pole of the battery, said plate having a raised socket piece 60 9 within which is a depression 10 to receive a paper cap or other explosive device for a purpose to be hereinafter described.

A striker or actuator 11 is attached to the base 8, in the form herein shown this striker having spring qualities sufficient to force it sharply against the bottom of the depression 10 to explode a cap therein. This striker is suitably connected with the pole of the battery opposite to that above mentioned, and a contact 12 projects from its under side in position to make contact with the terminal 7 under certain conditions, thereby completing the electric circuit to display the light. 75

A trigger 13 is pivotally attached to the base and a finger 14 projects laterally from the trigger to engage a horn 15 extending from the end of the striker 11, and as illustrated in Figure 1 of the drawings. The finger 14 is of cam shape so that when the striker 11 is in the position shown in full lines in Figure 1 it will engage the horn 15 and raise the striker sufficiently to disengage the contact 12 from the terminal 7, as shown in Figure 4, to break the electric circuit and extinguish the light. The resiliency of the parts will be sufficient to enable the contacts to be closed together by a slight pressure upon the trigger 13 for a temporary display of the light. If it is desired to prolong the display of the light the trigger may be moved into the position shown in dotted lines in Figure 1, the pivotal connection of the trigger 13 to the base being sufficiently loose to enable this lateral movement of the trigger. In order to disengage the terminal and contact an ear rest 16 is provided on the under side of the trigger 13 to rest against the base when the parts are 100

in the position shown in full lines in Figure 1 and this ear will engage the shoulder formed by the edge of the striker 11 located above the upper surface of the base and prevent lateral movement of the trigger until it is raised sufficiently to enable the ear 16 to pass over the top of the striker. A hole 17 or other means of attachment for a cord 18 may be provided at the outer end 10 of the trigger 13 as one means for actuating the device.

In operation the trigger 13 will be raised to its set position and as illustrated in Figure 4 of the drawing, in which position the 15 contact and terminal will be separated. When the actuator or striker 11 is thus supported in its set position by the striker, the support will be so feeble that a slight jar will be sufficient to "spring" the mechanism 20 and permit the striker 11 to move forcibly into contact with a cap that has been placed in the depression 10. The flashlight may be set upon the floor close to a door whereby it will be knocked over and operated in 25 the manner just described, should the door be opened. The flashlight may be laid on its side on the floor as illustrated in Figure 3 and the contact of the door with the trigger 13 will cause the parts to be operated 30 as hereinabove described or the cord 18 may be attached to a door or window in a manner to cause a pull upon the trigger 13 and its operation as hereinbefore described, to explode the cap and also to close the electric 35 circuit and display the light.

In the form of the device illustrated in Figure 5 the case 19 of ordinary construction is provided with a plunger socket 20 on its side within which a striker plunger 40 21 is located to be forced in one direction as by means of a spring 22. The end of the plunger is adapted to strike a cap that may be placed upon an anvil 23 located in the lower end of the socket. A setting lug 45 24 projects from the side of the plunger to engage a setting socket 25 and also to engage an anti-lighting socket 26 when in another position. When engaged with the setting socket the device will be in position 50 for operation and the support of the plunger setting lug will be so feeble that a slight jar will be sufficient to disengage the setting lug from its socket and permit the spring to force the plunger downwardly into contact 55 with a cap on the anvil to explode the cap. When the lug is in engagement with the socket 26 the plunger will be raised sufficiently to disengage the electrical contacts and extinguish the light, such contacts being in engagement when the plunger is in its lowermost position and the light being 60 thereby displayed.

The end of the plunger has a contact actuator 27 beveled on one edge so that it 65 will strike a contact 28 and force it into en-

gagement with a terminal 29 on the battery thereby completing the electric circuit and causing the light to be displayed in a manner that will be readily understood. This actuator may be of wedge-shape so that it 70 may be inserted in the crack between the door and a jamb so that if the door is opened to a slight extent the actuator will be freed, the case will drop and the jar will cause the cap to be exploded and the light 75 to be displayed, the torsion on the spring aiding in disengaging the lug 24 from the socket 25 to accomplish this purpose.

I claim—

1. A flashlight including a case, a battery, 80 an electric lamp electrically connected with the battery, a battery terminal and a terminal movably mounted to make contact with the battery terminal, an actuator movably mounted on the case and spring pressed 85 to move in one direction to effect contact of said terminals to electrically energize the lamp, and means for feebly holding the actuator in a set position.

2. A flashlight including a case, a battery, 90 an electric lamp electrically connected with the battery, a battery terminal and a terminal movably mounted to make contact with the battery terminal, an actuator movably mounted on the case and spring pressed 95 to move in one direction to effect contact of said terminals to electrically energize the lamp, means for feebly holding the actuator in a set condition, and means to receive an explosive device in position to be struck by 100 said actuator.

3. A flashlight including a case, a battery, 105 an electric lamp electrically connected with the battery and a battery terminal, an actuator urged to move in one direction and having a contact to make contact with the battery terminal when the actuator is in its closed position, a trigger to movably engage the actuator and feebly support it in set position, and means to receive an explosive device in position to be struck by said actuator.

4. A flashlight including a case, a battery, 115 an electric lamp electrically connected with the battery and a battery terminal, an actuator urged to move in one direction and having a contact to make contact with the battery terminal when the actuator is in its closed position, and a trigger arranged to normally overlie the actuator and hold said 120 terminals apart.

5. A flashlight including a case, a battery, 125 an electric lamp electrically connected with the battery and a battery terminal, an actuator urged to move in one direction and having a contact to make contact with the battery terminal when the actuator is in its closed position, and a trigger arranged to normally overlie the actuator and hold the terminals apart, said trigger and actuator 130

being sufficiently resilient for engagement of the terminals by pressure upon the trigger.

6. A flashlight including a case, a battery, an electric lamp electrically connected with the battery and a battery terminal, an actuator urged to move in one direction and having a contact to make contact with the bat-

tery terminal when in its closed position, and a trigger arranged to normally overlie the actuator to hold the terminals apart but 10 movable to an extent to permit disengagement of the actuator to permit the terminals to be brought into contact.

CHARLES A. BAILEY.
